UNITED STATES PATENT OFFICE.

WILLIS W. TAINTER, OF DIXFIELD, MAINE.

MACHINE FOR ROUNDING SPLINTS.

1,366,035.

Specification of Letters Patent. Patented Jan. 18, 1921.

Application filed October 6, 1919. Serial No. 328,647.

To all whom it may concern:

Be it known that I, WILLIS W. TAINTER, a citizen of the United States, residing at Dixfield, county of Oxford, State of Maine, have invented a certain new and useful Improvement in Machines for Rounding Splints, of which the following is a specification, reference being had therein to the accompanying drawings.

10 The invention relates to an improvement in machines for rounding splints, being especially intended for application to a machine for rounding toothpick splints, but it is understood that the invention is applicable to machines for rounding splints employed for any other use; for instance, skewers, dowels, match splints or any other kind of wood splints which when first formed are of angular shape in cross-section and require to be rounded either into circular form in cross-section or merely to have the corners rounded off.

15 The invention will be fully understood from the following description when taken in connection with the accompanying drawings, and the novel features thereof will be pointed out and clearly defined in the claims at the close of this specification.

20 In the drawings, Figure 1 is a plan view, partly broken away, of a machine embodying my invention.

Fig. 2 is a vertical section on line 2—2 of Fig. 1.

Fig. 3 is a vertical section to show more in detail the presser mechanism for pressing the toothpicks in the holder against the grinding wheel.

Fig. 4 is a detail view showing the delivery chute in relation to the toothpick holder.

40 Fig. 5 is a view showing a modified form of extracting mechanism.

Inasmuch as it is not necessary that the splints shall travel the entire circuit of the carrier, there is ample room for two sets of chutes and presser mechanisms in connection with the same machine, thus doubling the capacity of the machine. The drawings show the duplex form of apparatus, being provided with two feed chutes, two sets of presser rolls and two sets of discharge devices, as will be seen in Fig. 1. A description of one set answers for both.

Referring now to the drawings, 1 repre-

sents the bed plate which is preferably of circular form mounted on any suitable support (not shown). Secured to the under-side of the bed plate is a bracket 3 which is provided on its under side in the middle thereof with a stationary hub 4, through which extends a vertical shaft 5. Said shaft 60 5 is journaled at its upper end in a bearing 6 and at its lower end it is provided with a thrust bearing of any suitable form. In the form shown, this thrust bearing consists of a flange shell 7 secured to the lower end of the shaft 5, which co-operates with a flange shell 8 mounted on the upper end of a screw-threaded stem 9 which is threaded through a tapped-out sleeve 10 rigidly secured to the under side of the hub 4. The two members 70 7 and 8 are channeled out to receive the ball-bearings 11. The screw 9 is provided with a handle 12 whereby it may be turned to raise or lower it to adjust the thrust bearing for the shaft 5 up or down.

The bearing 6 is supported by a bracket arm 56 which extends diametrically over the top of the grinder wheel and carrier and has downwardly extending legs which are supported on the bed plate 1.

Mounted on the shaft 5 is a grinding wheel 13 preferably of emery. The shaft 5 is screw-threaded for a portion of its length, as shown at 14. There are also provided the two plates 15 and 16 which are screwed onto the shaft 14, one being above the grinding wheel 13 and the other being on the under side of the grinding wheel 13 to steady the grinding wheel and keep it from becoming loose on the shaft. These plates which are substantially cylindrical nuts are set up to firmly bear against the upper and lower faces of the grinding wheel.

Mounted fast on the shaft 5 is a driving pulley 17 connected in any suitable way 95 with the driving mechanism for rotating the shaft at any speed desired. The shaft may, however, be driven by any other suitable means, the particular method not being important.

A cylindrical shell 18 has a base portion 19 which is co-axial with the grinding wheel 13 and formed with a hub 20 through which the shaft 5 passes loosely. The base portion 19 bears on the bed plate 1, and in order to 105 avoid the friction which would result if the

entire surface was in contact, the base 19 of the shell has an annular flange 21 which serves as the bearing portion. Said shell 18 is rotatable on its axis and the bed plate 1 5 forms a support for the cylindrical shell through the annular flange 21 during the rotation.

The shell 18 is rotated independently of the rotation of the grinding wheel. The 10 means shown for giving rotation to the shell 18 is a driving shaft 22 provided with a worm 23 which engages with a worm wheel 24 mounted fast on the hub 20 of the shell 18. Any other suitable means, however, of rotating 15 the shell 18 may be employed.

Mounted on the upper side of the flange rim of the shell 18 is a splint carrier consisting of a ring 25 which is secured by screws 2 to the shell 18 so as to rotate there- 20 with. This ring lies just above the upper surface of the grinding wheel 13 and is provided with a series of splint-holding slots or pockets 26, which extend in a radial direction transversely of the ring 25. Each of 25 these slots is of sufficient length to receive one of the splints which is to be ground, and extends vertically through the ring 25, that is the slots are open at top and bottom so that when a splint is inserted in a slot, it will 30 rest upon the surface of the grinding wheel 13 and ride on the grinding wheel.

The driving mechanisms for the grinding wheel and for the splint-holding ring 25 are so adjusted and connected that the grinding wheel and the splint-holding ring will 35 rotate in opposite directions to each other.

If the machine is to be adapted for use in rounding double pointed toothpick splints, the grinding wheel will preferably have the 40 grinding surface 27 concaved in a radial direction in that portion of its surface which engages the splint beneath the splint-holder ring 25, as shown in Fig. 2, the concave form being of corresponding contour to the 45 lengthwise contour of the finished toothpick.

The splints are delivered to the pockets of the rotary splint carrier through a chute 28, the chute 28 being of a width substantially equal to the length of the splint or a trifle more, so that the splints will slide down the chutes broadside and be thence carried onto the upper side of the splint carrier ring 25 and the splints will fall into the pockets 26. The chute 28 is preferably provided with an 50 apron 29 at its lower end onto which the splints drop through the lower end of the chute to be delivered to the splint carrier. Preferably also this apron is provided with a plurality of forwardly extending fingers 55 30, 31 and 32, which extend into annular grooves 33, 34 and 35 respectively, in the splint carrier, these grooves extending through the partitions 36 which separate the pockets of the splint carrier. These fingers 60 hold the splints at first out of contact with

the grinding wheel and at a sufficient elevation so that the pocket will not retain one splint on top of another.

Mounted above the apron fingers at an elevation slightly above the path of the splint carrier is a doctor roll 37, which is rotatable and formed with a knurled periphery. It is made to rotate in the reverse direction to the direction of travel of the splint carrier, and extends down low enough so that if by 75 chance any splints are piled up or riding one on top of another, the doctor roll will engage the uppermost splint and throw it out of the way.

Any suitable means for rotating the doctor roll may be employed, the means shown being as follows:—

Mounted on the shaft of the doctor roll is a bevel gear 38 which engages with a bevel gear 39 on the vertical stud shaft 40 journaled in a bracket 41. The bracket 41 is supported by the arm 56. The lower end of said shaft 40 carries a spur gear or pinion 42 which engages with a large spur gear 43 connected with or forming part of the cylindrical shell 18.

The carrier ring 25 and the grinding wheel 13 are made to rotate in opposite directions to each other, preferably the grinding wheel being made to rotate at a much 95 greater speed than the carrier ring. The grinding operation need take place only during a very small portion of the travel of the splint in the carrier.

It is important that positive means be employed to rotate the splints on their axis during the grinding operation. Means provided for rotating the splints are as follows:—

A rotary presser wheel 44 is mounted on a 105 rotary shaft 45, said presser wheel being mounted so that its periphery will extend down into the middle groove 34 of the three grooves in the partitions 36 between the pockets of the splint carrier. The said 110 wheel is adjusted so that it will extend down into the groove a sufficient distance to engage the splints as they pass under the said presser wheel and to press them with an elastic pressure down against the surface 115 of the grinding wheel. Preferably, these presser wheels are made of elastic rubber or some other resilient substance. They are driven in the opposite direction to the direction of travel of the grinding wheel and 120 may be driven by proper gear connections with the gear 43. In the construction shown in the drawings, the shaft 45 is journaled in a bracket 46 and carries at its inner end a bevel gear 47 which meshes with a bevel gear 48 mounted on the shaft 49, the lower end of said shaft 49 carrying a spur gear wheel 50 which engages with the gear wheel 43.

The presser wheels 44 are adjustable vertically so as to increase or diminish the pres- 130

sure upon the splints as required. This adjustment is accomplished by making the bracket 46 vertically adjustable on the supporting bracket 57 with which it is connected, said supporting bracket 57 being provided with a vertical elongated slot 59 and the bracket 46 being connected with said support 57 by a screw 58 which passes through the elongated slot and the bracket 10 46, the screw having a clamping flange by which the two brackets are securely clamped together when the screw is set up. By raising or lowering the bracket 46, the presser wheel 44 will be raised or lowered as well as the shaft 45, carrying with them the bevel gear 47. The shaft 49 with its wheels 48 and 50 will also be raised and lowered accordingly.

Convenient means for raising and lowering the bracket 46 when the flanged screw 58 is loosened are shown in Fig. 3. The means provided are as follows:—A worm screw 60 has a smooth portion 61 which passes loosely through an aperture in an arm 62 which projects from the frame 57, the threaded portion of the screw working within a tapped-out hole 63 in the bracket 46. The worm screw is provided with collars 64-65 just above and just below the arm 62 respectively so that when the said worm screw is rotated it will raise or lower the bracket 46 according to the direction of rotation while the worm screw neither rises nor falls. Said worm is provided with a wheel handle 66 at its upper end by which it may be conveniently rotated.

In order that the splints may be kept from jumping out of the pockets after they pass beneath the doctor roll 37 and until after they have passed beyond the presser wheel there are provided the parallel guard rails 51 which follow the curved line of the grooves 33 and 35 in the splint carrier and extend down into the grooves a sufficient distance to prevent the splints from jumping out but not sufficient to form any frictional engagement with the carrier.

Preferably, there are provided two of the presser wheels 44 similarly mounted, one being located in a position to engage the splints just beyond the point where they pass out from beneath the first presser wheel. As the grinding wheel rotates very much faster than the presser wheel, each splint would be rotated quite a number of times while it is passing under the first presser wheel, but in order to insure a sufficient amount of abrasion or rounding of the splint, the second presser wheel is provided. By the time the splints have passed beyond the second presser wheel, they will ordinarily be sufficiently rounded for the purpose in view. There may still be more or less tumbling or rotation of the splints 60 65 while they lie loosely in the pockets by

reason of the fact that the grinding wheel moves at a considerably faster speed than the carrier and in the opposite direction thereto, but this will be slight and is immaterial.

At some point beyond the point at which the splints pass from beneath the second presser wheel they will be discharged from the pockets. One means of discharging or withdrawing them from the pockets is to provide a suction device 52 which is not shown in detail, but any well-known form of suction device may be employed. The portion 52 shown in the drawing is merely a representation of the mouth of the suction device.

A modified form of extractor is shown in Fig. 5 in which the extractor consists of a rotary wheel 53 having in its periphery a series of needles or pricks 54, spaced apart from each other on the periphery equal to the distance between the successive splints in the successive pockets. The said extractor wheel should be made to rotate at the same rate of speed as the splint carrier so that one of the needles will be brought into position to engage one of the splints as fast as the splints are fed. These needles will catch the splint and hold it long enough to lift it out of the carrier, and in the further rotation of the extractor wheel the splint will be engaged by a finger 55 which will disengage the splint from the needle and cause it to fall into a suitable receptacle provided for the purpose.

What I claim is,

1. A machine for rounding splints having a rotary wheel formed with an abrading surface on one side face thereof, and mounted to rotate in a horizontal plane, a rotary carrier ring mounted immediately above and coaxial with said abrading wheel, said carrier ring being formed with radially disposed splint-receiving pockets, each adapted to hold a single splint lying lengthwise of its axis on the side face of the abrading wheel, the carrier moving the splints in a circular path concentric with the abrading wheel in a plane at right angles to its axis, and a rotary presser wheel whose periphery engages each splint in its pocket at a certain point in the travel of the splint and rotates the splint on its axis and at the same time positively holds it in contact with the abrading wheel.

2. A machine for rounding splints having a rotary wheel formed with an abrading surface on one side thereof and mounted to rotate in a horizontal plane, a rotary carrier ring mounted immediately above and co-axially with said abrading wheel, said carrier ring being formed with radially disposed splint-receiving slots each adapted to receive a single splint lying on the surface of the abrading wheel, and means for rotat-

ing the splint on its axis and at the same time positively holding it in contact with the abrading wheel, the partitions between the slots being formed with transverse grooves, 5 means for feeding splints to the carrier at a station prior to the point where the splints pass under the mechanism for rotating them on their axis, a stationary apron having fingers which extend into the grooves in the 10 partitions of the carrier as they pass around and which receive the splints from the feed, and a clearance member which rotates on a stationary axis above the fingers and has a clearance space therefrom to allow the thickness of only a single splint in a slot to pass under it.

3. A splint rounding machine having a rotary grinding wheel with an abrading surface on one of its side faces, a rotary 20 annular splint carrier co-axial with the grinding face of said grinding wheel and lying in close proximity thereto, said splint carrier being formed with radial pockets therein open at the top and bottom within 25 which the splints may lie in contact with the face of the grinding wheel, means for rotating both the splint carrier and the grinding wheel, the partitions between the pockets being formed with a plurality of 30 annular grooves which extend transversely through the partitions between the pockets, a feed chute for the splints located above 35 the path of travel of the splint carrier, and having an apron formed with splint supporting fingers which extend down into said 40 grooves in the carrier to temporarily support the splints above the surface of the grinding wheel, and a doctor located above the said fingers in sufficient proximity thereto to clear out of the pocket any surplus 45 splints over the single splint which the pocket is intended to hold.

4. A splint rounding machine having a rotary grinding wheel with an abrading surface on one of its side faces, a rotary 45 annular splint carrier co-axial with the grinding face of said grinding wheel and lying in close proximity thereto, said splint carrier being formed with radial pockets 50 therein open at the top and bottom, within which the splints may lie in contact with the face of the grinding wheel, means for rotating both the splint carrier and the grinding wheel, the partitions between the pockets being formed with a plurality of 55 annular grooves which extend transversely through the partitions between the pockets, a feed chute for the splints located above the path of travel of the splint carrier, and 60 having an apron formed with the splint supporting fingers which extend down into said grooves in the carrier to temporarily support the splints somewhat above the surface of the grinding wheel, a doctor located 65 above the said fingers in sufficient proxim-

ity thereto to clear out of the pocket any surplus splints over the single splint which the pocket is intended to hold, and a rotary presser roll which extends down into one of the intermediate grooves in the carrier 70 and engages each splint as it passes under the roll and presses it into engagement with the grinding surface.

5. A splint rounding machine having a rotary grinding wheel mounted on a vertical axis and having an abrading surface on its upper side face, a rotary annular splint carrier co-axial with the grinding face of said grinding wheel and lying in close proximity thereto above the same, said splint 75 carrier being formed with radial pockets therein open at the top and bottom within which the splint may lie in contact with the face of the grinding wheel and may be moved thereby over the surface of the 80 grinding wheel, said splint carrier being formed with an annular groove which extends transversely through the partitions between the pockets, a rotary presser wheel mounted above the splint carrier whose periphery extends down into said groove and engages each one of the splints as it passes beneath said presser roll, thereby rotating the splint on its axis while it is engaged by the grinding surface.

6. A splint rounding machine having a rotary grinding wheel mounted to rotate in a horizontal plane on a vertical axis and having an abrading surface on its upper side face, a rotary annular splint carrier 100 co-axial with the grinding face of said grinding wheel and lying in close proximity thereto above the same, said splint carrier being formed with radial pockets therein open at the top and bottom, within which 105 the splint may lie in contact with the face of the grinding wheel and may be moved thereby over the surface of the grinding wheel, said splint carrier being formed with three concentric annular grooves 110 which extend transversely through the partitions between the pockets, means for delivering the splints onto the said carrier, means for clearing out of each pocket all but a single splint, guards which extend down into the outer and inner annular groove for some distance beyond the point at which the splints are received, and extend crosswise of the splints near their outer ends, a rotary presser roll whose periphery extends down into the intermediate 120 annular groove and engages with each splint as it passes under it, and means for rotating said presser roll thereby causing the splint to rotate on its axis.

7. A splint rounding machine having a rotary grinding wheel mounted on a vertical axis and having an abrading surface on its upper horizontal side, a rotary annular splint carrier co-axial with the grinding 130

face of said grinding wheel and lying in close proximity to the upper face thereof, said splint carrier being formed with radial pockets therein open at the top and bottom 5 within which the splints may lie in contact with the abrading face of the grinding wheel, means for rotating both the splint carrier and the grinding wheel, the splint carrier being formed with partitions between the pockets and being formed with an 10 annular groove which extends transversely through the partitions between the pockets, and a rotary presser roll which extends down into said groove and engages each 15 splint as it passes under the roll and presses it into engagement with the grinding surface.

8. A splint rounding machine having a rotary grinding wheel mounted to rotate in a horizontal plane on a vertical axis and having an abrading surface on its upper side face, a rotary annular splint carrier co-axial with the grinding face of said grinding wheel and lying in close proximity thereto 20 above the same, said splint carrier being formed with pockets therein within which the splints may lie in contact with the face of the grinding wheel, the partitions between said pockets being formed with annular grooves which extend transversely 25 through said partitions, means for delivering splints into said pockets, and guards which extend into said grooves in the direction of the travel of the carrier for some 30 distance beyond the point at which the splints are received and lie crosswise above the splints.

9. A machine for rounding splints having a rotary grinding wheel, one side of which has an abrading surface, a rotary carrier wheel mounted co-axial with said grinding wheel and having one face in close proximity to the abrading face of the grinding wheel, said carrier being formed with a plurality of elongated slots forming pockets each adapted to receive a splint in such manner that the splint lies lengthwise on the abrading surface of the grinding wheel, a rotary presser wheel located above the path 45 of the splint in position to engage the splint when the splint passes beneath the presser wheel, means for rotating the splint carrier and presser wheel, means whereby the rotation of the splint carrier controls the rotation of the presser wheel, and independent means for rotating the grinding wheel.

10. A machine for rounding splints having a rotary grinding wheel, a rotary splint carrier adapted to hold splints in spaced relation on the grinding surface of the grinding wheel, a rotary presser wheel mounted on a stationary axis and having a periphery which engages each splint as it passes beneath the presser wheel, means for 60 rotating the splint carrier and the presser 65

wheel, means whereby the rotation of the splint carrier controls the rotation of the presser wheel, and independent means for rotating the grinding wheel.

11. A machine for rounding splints having a rotary grinding wheel which rotates in a horizontal plane, a vertical shaft on which said grinding wheel is mounted, a shell having a hub through which said shaft loosely passes, said shell having an upwardly extending annular flange which loosely surrounds the periphery of said grinding wheel, an annular splint carrying wheel secured to said flange and extending over the upper face of said grinding wheel, said splint carrier being formed with slots to receive the splints, each slot being open so that the splints as they lie in the slots will rest on the surface of the grinding wheel, and means for independently rotating said 70 75 80 85 grinding wheel shaft and the shell which carries the splint carrier.

12. A machine for rounding splints having a rotary grinding wheel which rotates in a horizontal plane, a vertical shaft on which said grinding wheel is mounted, a shell having a hub through which said shaft loosely passes, said shell having an upwardly extending annular flange which loosely surrounds the periphery of said 90 95 100 105 grinding wheel, an annular splint carrying wheel secured to said flange and extending over the upper face of said grinding wheel, said splint carrier being formed with slots to receive the splints, each slot being open so that the splints as they lie in the slots will rest on the surface of the grinding wheel, a rotary presser wheel which is mounted to engage with each one of the splints at a certain point in the rotation of the splint carrier, means for rotating the grinding wheel, and means for rotating said 110 115 120 125 splint carrier and presser wheel.

13. A machine for rounding splints, having a rotary grinding wheel, a rotary shell on which a splint carrier is mounted co-axial with said grinding wheel, the splint carrier extending over the top of the grinding wheel and being formed with slots within which the splints are held, said slots being open at the bottom so that the splints will engage with the surface of the grinding wheel, a rotary presser wheel located above the splint carrier in position for the said presser wheel to engage with each one of the splints at a certain point in the travel of the splint during the rotation of the splint carrier, means for rotating the mount for the splint carrier, means whereby the rotation of the splint carrier mount actuates the presser wheel, and means for vertically adjusting the presser wheel.

14. A machine for rounding splints having a rotary grinding wheel, a rotary shell on which a splint carrier is mounted co-axial 130

- with said grinding wheel, the splint carrier extending over the top of the grinding wheel and being formed with slots within which the splints are held, said slots being open 5 at the bottom so that the splints will engage with the surface of the grinding wheel, a rotary presser wheel located above the splint carrier in position for the said presser wheel to engage with each one of the splints at a 10 certain point in the travel of the splint during the rotation of the splint carrier, said shell on which the splint carrier is mounted

having peripheral gear teeth, means for rotating said shell, a vertically adjustable bracket having journaled therein a shaft on 15 which said presser wheel is mounted, and a second shaft mounted in said bracket having gear connection with said shell and also having gear connection with the presser wheel shaft, said bracket being vertically adjustable to vary the elevation of the presser wheel.

In testimony whereof I affix my signature.
WILLIS W. TAINTER.
